ASH REMOVAL SYSTEM FOR TRUCKS

Neil H. Gebhardt, Erie, Pa.

Application November 19, 1953, Serial No. 393,198

14 Claims. (Cl. 214—508)

This invention relates to ash removal systems and has for its principal object the provision of a tank in which the usual filter is omitted as the air for the fan may be taken directly from the tank.

A further object of the invention is to provide a truck carried tank which serves as a natural separator for the solid particles, discharging these at high velocity so that as the solid particles impinge against a barrier they fall inert to the bottom of the tank and the tank will be filled progressively from the lower front corner to the upper rear margin of the tank, the air intake and the air outlet being located in the latter position. This permits the filling of the tank to near capacity without obstructing either the inlet or the outlet.

A further object of the invention is to provide a system wherein a controlled portion of the pressure air is bled from the closed system at a point close to the fan discharge. This permits control of the vacuum that pulls ash into the conveying system and provides the capacity to handle ash in the tube of the vacuum line.

Other objects of the invention are covered in the separate claims and include the use of a sudden blast of air to start the flow of ashes when there has been a cessation of flow, the provision of a simple and efficient method of dumping the ashes collected by the pressure-vacuum system and the convenient location of the various elements of the system on a vehicle of the usual dump-truck type, either as a permanent part of the truck or as a unit which can be installed temporarily in an ordinary dump-truck, which at other times may be used for other work.

In previous closed vacuum conveying systems, it has been customary and necessary to employ either a filter or a separator, such as a cyclone separator, to clean the air as it leaves the vacuum tank in which solids are deposited and before it enters the fan intake. Filters set up resistance to the flow of air through the system. When the filters are clean, resistance is at a minimum. As they become progressively filled with dust, resistance interferes with satisfactory control of the air stream, in spite of many devices for reversing the air through the filters, etc. In the present device, as in earlier arrangements, there is a closed system, a fan or blower providing pressure, suction, and a neutral point the latter generally beneath the receptacle in the dwelling. Without filters, the flow of air is not restricted and is constant rather than variable.

The truck which carries the fan, receives the ashes, has a steel pipe pressure line and a steel pipe vacuum line and these are connected by hoses to the corresponding permanent pipes extending thru the dwelling wall so that when the ashes are to be removed it is merely necessary to connect the hoses, start the fan, usually without even the necessity of entering the home. The present invention simplifies the mobile portion of the system and by virtue of the high velocity given to the discharge vacuum pipe the ashes impinging upon a plate fall inertly to the bottom of the tank making it possible to draw air for the fan from a point at the opposite end of the tank and

2

without the need for a filter or any type of solids separation other than that which is provided by the tank itself.

In such a system it is necessary to bleed off a portion of the pressure air in order to develop the vacuum required to pull ash into the air stream and provide capacity to convey it in the tube of the vacuum line. To accomplish these purposes the present invention contemplates selectively withdrawing a portion of the pressure air and feeding this to exhaust bags furnished with zippers and acting much as the bag in an ordinary household vacuum cleaner type, the principal difference being that in this device the dust is extremely fine and is entirely free from what would ordinarily be called ashes.

In the drawings:

Figure 1 is a side elevation;
Figure 2 is a plan view;
Figure 3 is a rear elevation of the tank;
Figure 4 is a transverse vertical section on line 4—4 of Figure 2.

15 The ash removal unit of the present invention includes an air-tight tank 10 mounted on a truck, the cab of which is 11 and the rear wheels are 12. The tank is of the dump-truck type being pivoted as at 14 to the truck body in well known and old fashion. A portion of the tank 10, hereinafter called the cabinet and numbered 15, is formed in the upper rear portion of the dump body by means of a vertical wall 16 and a horizontal wall 17. The cabinet conveniently receives the major portion of the equipment including a fan 20, the shaft 21 of which is mounted in bearings 22 and 23, and carries at its free end a pulley 24 driven by belt 25 from a drive wheel 26 on the shaft 27 of a hydraulic motor of standard type driven by a pump (neither shown) from the usual power take-off device of the truck.

20 30 35 The pipe 30 extends horizontally from the intake side of the fan thru a flanged end 31 and then turns upwardly ending in a funnel-shaped air entry end 32 located very close to the top wall or ceiling 35 of the tank 10. The latter is provided with a manhole having the cover 37 for convenient access to the interior of the tank. Air thus passing from the tank to the fan 20 is discharged thru pressure pipe 40 to the coupling end 41 in convenient position at the very back of the truck for receiving the hose, not shown, leading to the dwelling pipes.

40 45 As best seen in Figure 1, the tank 10 has a rear portion 28 between the partition 17 and the floor 29 thru which the ashes may be discharged when the front of the dump body is raised about the pivot 14. The discharge is in the center and is controlled by the gate 33, hinged as at 34. Where the number of houses to be served is quite 50 small, it is sometimes convenient to form the tank into a detachable portion so that it can be mounted in a dump-truck and used exactly as described here but being readily detachable can be used say one day in ten, while the dump-truck may be used for other purposes on the other nine days or thruout the summer months.

55 The pressure line 40 is provided with two bleed lines 44 and 45, each provided with a control valve 46 or 47 by means of which any desired amount of bleeding can be set for thru either or both of the lines 44 and 45. Each 60 of the two lines extend thru the wall 48 of the tank into a small side closet 49 on each side of slight depth and having doors 50 for access to the exhaust bag 51 suspended in the closet by means of tabs 52 and having a nipple 53 to slide on the free end 54 of the bleeder pipe 44 or 45. In 65 order that these bags may have a large free surface for escape of the air, the bag closets 49 are lined with large mesh fencing wire 55 to keep the bag from touching the smooth wall, thereby allowing freer passage of air. The bags each have the usual zipper 56 so the bag can conveniently be turned inside out.

70 The house vacuum line, not shown, may be connected by

a hose to the coupling 59 of the steel vacuum line 60 at the center of the rear of the vehicle in line horizontally with the pressure pipe coupling end 41. The vacuum line rises to a point near the top 35 of the tank, passes thru the partition 16 which divides the cabinet from the tank and there carries a nozzle 62. This nozzle has a sloping discharge end 63 so that the ashes tend to be directed slightly downward from horizontal and therefore the stream, which is highly abrasive, is guided away from top 35 and strikes against the wear-plate 65 which is of heavy gauge metal. It is convenient to mount this plate on double flanged angles 66 welded to the front of the tank, this arrangement permitting the wear-plate to be bolted to the angles and therefore to be readily removable and a bit flexible, thus allowing the use of much thinner plates than would be required if the wear-plate were permanently secured to the tank.

In use when the hoses are coupled to the dwelling pipes and to the pressure line 41 and the vacuum lines 60, the hydraulic motor is started, having the usual control at the very back of the truck where it is most convenient for the operator. This control forms no part of the invention and the power that drives the fan can be of any type. The hydraulic motor has been found in practice to be very satisfactory because of its size, the convenience and ease with which it operates the fan at its rated speed of about 3,500 R. P. M. This speed amply provides the desired velocity in the air stream and requires only seven horse power for its operation. Generally the starting of the fan starts the flow of ash but if there is any difficulty in starting, the blast gate 70, Figure 2, is suddenly open and closed thus giving a jarring action in the air stream that will dislodge any packing or arching of ash that might develop above the points of pickup and interfere with the entry of ash into the air stream. The ashes enter through line 60 and are discharged horizontally into the tank through nozzle 62. They are discharged at such high velocity that they travel the length of the tank, impinging sharply against wear plate 65. The passage of air, as it returns to the fan intake at the opposite end of the tank, is through the entire cross-sectional area of the tank and the movement is so slow that solids cannot be carried in it. The lower corner directly below the wear plate is filled first and as ashes continue to pile up, the ash surface rises at an angle to horizontal and vertical and slowly approaches the upper corner at the opposite end of the tank, near the discharge point 62 and the intake pipe 32. Because the ashes fall quite dead at impact and because of the pattern of ash accumulation in the tank, it can be filled to near total capacity and continue to deliver to the funnel intake 32 air that is perfectly satisfactory to pass through the fan without the requirement of passing it through a filter or separator. This may seem odd, but the device has been in use for months without the fan showing any appreciable wear. In fact, after handling approximately 100 tons of ash, the fan was disassembled for inspection. There was not even evidence of wear on the surface of the paint that coated the fan blades. The fan discharges pressure air through pipe 40 and, as conditions warrant, the amount of bleeding through pipes 44 and 45 is controlled and adjusted by either or both of the valves 46 and 47. The flow of ashes against wear plate 65 and in vacuum pipe 60 can readily be heard and, when this sound ceases, the house receptacle is usually empty. Infrequently, there is packing or arching of ash in the receptacle above the openings through which ash enters the air stream. The sudden opening and closing of the blast gate 70 will re-establish the flow of ash. If this action does not re-establish a flow of ash, the operator may be sure the receptacle is empty.

What I claim is:

1. In combination, a chassis, a dump body pivotally carried by the chassis to move about a pivot at the rear of both chassis and dump body, an air tight tank forming a position of the dump body, a pipe for discharging

ashes into the tank at high velocity against the front thereof, and a gate at the rear of the tank to discharge by gravity the contents of the tank when the dump body is in dumping position.

2. The combination of claim 1 in which the pipe is a portion of a closed system including a fan, a fan intake inside of the air-tight tank, near the top thereof, proximate the discharge end of said pipe, and a pressure pipe leading from the fan outside of the tank, whereby the tank is filled from the front toward the rear and the fan intake is still uncovered when the tank has been filled to the top at the front, and the fan intake lowers the pressure in the tank.

3. In combination, a motor driven truck, an air-tight tank pivotally carried by the truck, a variable speed hydraulic motor driven by the truck, a fan driven by the hydraulic motor, pressure and vacuum lines connected to the fan to form with an ash receptacle and the tank a closed ash conveying system, bleeder lines having valved connections with the pressure line, an ash discharge pipe in the tank forming a portion of the vacuum line, and a fan air inlet also in the tank.

4. The combination of claim 3 including a quick-acting blast valve in the vacuum line, whereby the sudden opening and closing of said valve will give a jarring action in the pressure air stream and thus re-establish the flow of ashes after any banking or arching thereof.

5. In combination, a closed tank, a pipe extending thru a wall of the tank and having a free end near the top of the tank for admitting air to a pressure-vacuum ash conveying system, an ash discharge pipe projecting thru said wall of the tank and discharging ashes against the opposite wall and means on the opposite wall for shielding the wall from the abrading action of the ashes, the inside end of the discharge pipe being located in proximity to the intake end of the air-admitting pipe.

6. The device of claim 5 in which said means includes a wear-plate detachably secured at its two sides to the opposite wall, and spaced from said opposite wall in order that the flow of ashes against the wear plate may the more readily be heard.

7. The device of claim 5 in which the means includes a pair of spaced vertical-channel irons fast to the opposite wall of the tank, and a wear-plate detachably secured to the channel irons.

8. In combination, a fan, a pressure line leading from the fan and adapted to be connected to a closed ash receptacle, a plurality of bleeder lines extending from the pressure line, a valve in each bleeder line, an exhaust bag connected to each bleeder line at the end thereof, a closed tank, an air pipe exhausting air from the tank and leading to the entry side of the fan, a vacuum line extending into the tank and adapted to be connected to said receptacle and forming with the pressure line, the receptacle, the tank, and the fan a closed system.

9. The device of claim 8 in which a quick-acting blast valve is located in the pressure line between the fan and the nearest of the bleeder lines to increase suddenly the vacuum in the vacuum line and increase the pressure in the pressure line, whereby to determine that a receptacle connected to the vacuum line and the pressure line has been completely emptied.

10. In a device for withdrawing ashes, a closed circuit including a fan, a tank, a vacuum line discharging ashes into the tank and a pressure line from the fan, a plurality of bleeder lines, a plurality of closed closets, one of said closets being on each side of the tank and each bleeder line leading from the pressure line, an exhaust bag within each closet and connected to the end of a bleeder line, and wire cloth lining the closet to keep the bag from touching the smooth wall of the closet whereby to increase the surface of the exhaust bag thru which air may pass, each of said closets being rectangular with a horizontal depth less than the horizontal width and the vertical height.

11. In an ash handling device, a power driven truck, a dump body pivoted at the rear thereof, an air-tight tank detachably mounted upon the dump body, a fan mounted on the outside of the tank, a pipe connected to the fan and extending into the tank for discharging ashes into the tank at high velocity against the front thereof, and a gate at the rear of the tank to discharge the contents of the tank when the dump body is in dumping position.

12. In combination, a chassis, a dump body pivotally carried by the chassis, an air-tight tank in the dump body, a pipe for discharging ashes into the tank at high velocity against the front of the tank, and a gate at the rear of the tank to discharge by gravity the contents of the tank when the dump body is in dumping position, said pipe having its discharge end close to the ceiling of the tank and the discharge end is sloping so as to direct ashes away from said ceiling.

13. A tank body for an ash removal truck including an air-tight chamber having opposite vertical walls, an ash discharging pipe of a closed system passing through one of said walls and discharging ashes against the opposite wall, an air-intake pipe forming a portion of said closed system and having its entry end inside the closed chamber proximate said one wall, said chamber being unobstructed between said pipes and said opposite wall, whereby air later withdrawn from the chamber through the intake passes through the entire transverse cross-sectional area of the chamber with such slow movement that the solids are deposited in the tank and a filter or separator is consequently unnecessary as the air when passing through the air intake pipe is thus substantially free of ash particles.

14. A vehicle for receiving ashes from a receptacle comprising a self-propelled chassis, a dump body pivotally carried by the chassis, and having therein an air-tight tank, a gate at one end of the tank for discharging by gravity the entire contents of the tank when the dump body is in dumping position, and means forming with the tank and the receptacle a closed pneumatic conveyor system for moving ashes from the receptacle to fill the tank, the discharge from the fan being the pressure line to the receptacle and the vacuum line of the system discharging ashes from the receptacle into the tank, the air withdrawn through the inlet, preserving the vacuum in the tank.
